UNITED STATES PATENT OFFICE.

GUST THOMAS, OF FORT SILL, OKLAHOMA.

DESIGN FOR AN INKSTAND.

55,898.

Specification for Design.

Patented July 20, 1920.

Application filed March 20, 1920. Serial No. 367,493. Term of patent 14 years.

To all whom it may concern:

Be it known that I, GUST THOMAS, a citizen of the United States, residing at Fort Sill, in the county of Comanche, State of Oklahoma, have invented a new and original Design for an Inkstand, of which the following is a specification, reference being had to the accompanying drawing, forming a part thereof.

The figure is a perspective view of the ink stand showing my new design.

I claim:

The ornamental design for an inkstand, as shown.

In testimony whereof I hereunto affix my signature in the presence of two witnesses.

GUST THOMAS.

Witnesses:

DOYER O. HICKEY,
PAUL E. HURT.
